UNITED STATES PATENT OFFICE.

ERNEST LUPTON ALLEN, OF BEOLEY, NEAR REDDITCH, ENGLAND.

NEEDLE-PACKAGE.

1,101,380.

Specification of Letters Patent. Patented June 23, 1914.

Application filed March 17, 1913. Serial No. 754,986.

To all whom it may concern:

Be it known that I, ERNEST LUPTON ALLEN, a subject of the Kingdom of Great Britain, residing at Fairview, Beoley, near 5 Redditch, in the county of Worcester, England, have invented certain new and useful Improvements in Needle-Packages, of which the following is a specification.

This invention relates to a means for 10 sticking needles in such a manner that the heads may be spread apart in one plane to a fan shape form so as to not only effectively display the needles, but render possible an 15 easy selection of any particular needle from the group, while at the same time such sticking is effected in an ordinary sticking machine.

In accordance with this invention the 20 sticking of the needles is effected in a flexible material, and in such a manner that while being capable of being opened out and displayed in the fan shaped form they may be again closed together into the parallel form 25 usual in the case of a packet of cloth stuck needles, and may be so arranged in cases or 30 wrappers that upon the opening of the case or cover the needles which are of parallel and close formation while in the case are automatically spread into the fan shape formation by the action of opening the case.

In order that this invention may be clearly 35 understood and more easily carried into practice reference may be had to the appended three sheets of explanatory drawings, upon which:—

Figure 1 illustrates the inner part of the 40 case containing needles, the sticking of which has been effected in accordance with these improvements. Fig. 2 is a similar view to Fig. 1, but illustrating the needles when expanded into the fan like formation. Fig. 3 shows the needle case complete with the outer casing and in the open position. Fig. 4 is a similar view to Fig. 3, but illustrates a modification whereby the expanding 45 of the needles is effected by the operation of opening the case. Fig. 5 is an elevation of the interior portion of the casing shown in Fig. 4 showing the needles in the closed or 50 normal position. Fig. 6 is an interior elevation of the outer casing shown in Fig. 4. Fig. 7 illustrates the application of the arrangement for display of the needles to a show card. Fig. 8 is an elevation showing 55 one application of the arrangement to a folding needle case, which case is shown

open. Fig. 9 is a view of the case shown in Fig. 8 illustrating the method by which the easy extraction of any needle may be attained. Fig. 10 is an elevation of the case 60 when closed.

In carrying this invention into effect the flexible material into which the needles are stuck preferably consists of a strip of india rubber *a* but may be of other material such as a strip of felt, leather, cork or cloth of sufficient thickness and closeness of texture.

The sticking of the needles is effected in parallel and close formation in an ordinary sticking machine and referring to Figs. 1 to 3 the flexible material into which the needles *c* have been stuck is attached at the ends *a*¹ to the inner part *b* of the needle case, a crank or cam arrangement *d* being provided and by the operation of which the flexible material is expanded into a circular shape, thus opening out the needles into the expanded formation shown in Fig. 2. If desired the extended ends *a*¹ of the flexible pad may be incased in metal having small grooves and 75 depressions, which small depressions *b*⁴ in the case *b* enter so as to allow the ends of the flexible material to have a limited amount of sliding action when the flexible material is operated upon by the part *d* and thereby 80 prevent the unequal distortion of the pad *a*. 85

In the modification illustrated by Figs. 4, 5 and 6, the flexible material *a* may be centrally secured in the inner case *b* by a small point *b*¹ in the metal entering the 90 face of the pad, a form of arch *d*¹ being provided under the center of the flexible material, so that as the projections *b*² on the sliding outer case *b*³ bear against the extremities *a*¹ of the flexible pad, such pad is 95 caused to take the position shown in Fig. 4, the needles being thereby opened out to the fan shaped formation upon the termination of the opening of the sliding case.

In the case of show cards the flexible 100 pad *a* may be bent to the required circle and inserted within a suitable slot such as *c*¹ in the show card *c* Fig. 7, being retained in position by an adhesive backing of canvas or other such material at the back of the 105 show card.

In the application to needle cases of a folding kind as shown in Figs. 8, 9 and 10, the flexible pad *a* is bent to a circle and secured in that condition to a suitable part 110 of the wrapper *f* preferably in such a position that by bending over the wrapper as

shown in Fig. 9 the needles can be readily extracted.

It will be obvious that the method of displaying the needles on show cards may be varied to a considerable extent as also the means for securing them in their fan shaped form upon such show cards, while the above described means for embodying such arrangement in conjunction with needle cases and folding wrappers of all classes are only examples to illustrate the general application which will thereby be readily understood.

What I claim as my invention and desire to secure by Letters Patent is:—

1. A needle package comprising a carrying part, a flexible needle holder secured to said part and adapted to receive needles and hold them normally on said carrying part parallel with each other, and means to flex said holder to hold the needles abnormally apart.

2. A needle package comprising a carrying part, a flexible needle holder secured to said part and adapted to hold needles in its normal non-flex position parallel with each other, and means to flex said holder to an abnormal position to spread the needles apart for display.

3. A needle holder comprising in combination, a flexible member adapted to receive the needles and to hold them normally parallel to each other, and means for retaining said member in a flexed or distorted condition to thereby separate those ends of the needles which are remote from the holder, substantially as set forth.

In witness whereof I have hereunto set my hand in the presence of two witnesses.

ERNEST LUPTON ALLEN.
